Fig. 1

Fig. 2

Fig. 3

FIG. 1 is a top plan view of a filling station sign embodying my new design;

FIG. 2 is a front elevational view thereof, the rear being a mirror image of the front shown; and

FIG. 3 is an elevational view taken from one end thereof, the opposite end being a mirror image of the end shown.

The broken line representation of indicia, gasoline pumps and an island in FIG. 2 are for purposes of illustration only.

I claim:

The ornamental design for a filling station sign, substantially as shown and described.
